H. M. COGAN.
FUSE FOR ELECTRIC CIRCUITS.
APPLICATION FILED APR. 13, 1917.

1,308,042.

Patented July 1, 1919.

INVENTOR

Henry M. Cogan

ATTORNEY

UNITED STATES PATENT OFFICE.

HENRY MANNING COGAN, OF BROOKLYN, NEW YORK.

FUSE FOR ELECTRIC CIRCUITS.

1,308,042.

Specification of Letters Patent.

Patented July 1, 1919.

Application filed April 13, 1917. Serial No. 161,886.

To all whom it may concern:

Be it known that I, HENRY MANNING COGAN, a citizen of the United States, and resident of the borough of Brooklyn, county of Kings, city and State of New York, have invented certain new and useful Improvements in Fuses for Electric Circuits, of which the following is a specification.

The device the subject of this invention is intended as a refillable cartridge fuse, and the invention resides primarily in the construction of the fuse, and in the means for retaining the fuse link or metallic strip, usually termed the fuse, in a proper position, and under conditions which, when the fuse is disrupted by an excessive current, will allow the ready insertion of a new fuse or fuse link.

The important features of the invention reside in the fact that the fuse as a whole may be used a great number of times, that the cartridge or container may retain fuse links of any desired capacity. That the device has all of the characteristics and advantages of the ordinary cartridge fuse and the added advantages which will be fully described as the specification progresses.

The following is what I consider a good means of carrying out this invention, and the accompanying drawings should be referred to for a full understanding of the specification which follows:

In the drawings:

Figure 1 shows a side elevation of a complete cartridge fuse.

Fig. 2 a partial sectional view of the device shown in Fig. 1.

Fig. 3 shows parallel fuse links.

Fig. 4 an end elevation.

Fig. 5 an end elevation of a part removed.

Fig. 6 an enlarged sectional view of one of the ventilating ports.

Similar reference numerals indicate like parts in all of the figures where they appear.

Like all cartridge fuses my device has a tubular container as shown at 1. This tubular member may be formed of fiber, glass or any other nonconductive material, and yet it is quite evident that I prefer to employ material that will withstand the pres-

sure generated by the rending of the fuse link as well as the heat due to the increase of current.

Arranged one at each end of the tubular member 1, are metallic caps 2 and 3, and 55 these caps are secured to the body or tubular member 1, by means of bolts 4 and 5, which pass quite through the caps, and through the member 1.

The caps 2 and 3 are formed as cups, and 60 are each provided with a plurality of perforations 6, 7, 8 and 9, which I may term ventilating ports, and which will be later described.

Each cap is provided with an elongated 65 slot 10, through which will project, what is sometimes termed the knife blades, and which are shown at 11 and 12, in Figs. 1 and 2. Additional perforations in the caps receive the securing screws 13 and 14, and 70 still further perforations 15 and 16 are for a purpose that will be later described.

As shown in Fig. 5, each of the knife blade members is provided with a plurality of outwardly extending lugs 17 and 18. 75 These lugs are in turn provided with screw threaded perforations 19 and 20, and when assembled the perforations 19 and 20 will receive the securing screws 13 and 14.

The fuse or link member is one of the 80 most important members of my device, and it may be made in a number of different ways. I have, however, on the fuse shown in the drawings used parallel fuse links as shown in Fig. 3, and the construction of 85 these links is clearly shown in Fig. 2.

Each link is provided with parallel arms 21 and 22, formed integral and joined by a loop or return bend 23. This loop or return bend passes over one of the lugs 17 or 90 18, and when the screw 13 or 14 is inserted through the return bend 23, and into the lug 17 or 18, the screw 13 draws the cap 3, downward or inward against the return bend 23, clamping the return bend of the 95 fuse in firm contact between the lug 17 and the cap 3. As the lug 17 is of metal, preferably copper, and the cap 3 is also of metal, preferably copper, it will be readily understood that a close and satisfactory electric 100

contact will be the construction shown be established between the fuse link and the knife blade 12.

The opposite ends of the arms 21 and 22 of the fuse link are bent to provide overlapping projections 24 and 25, and these projections are engaged (as shown in the drawing) upon the lug 18, formed integral with the knife blade 11, and the screws 14 and 14' engage the projections 24 and 25 against the lug 18, and cap 2, in the manner previously described.

As shown in Fig. 3 two fuse links A and B may be employed, and arranged parallel with each other, the securing bolts 4 and 5, passing between the two fuse links. I may perforate the links A and B, as shown at 26 and 27, weakening them at a definite point, the point where it is desired that they should part when an excessive current is passed through them.

I may provide depressions or serrations 28, 29 and 30 in the separate arms 21 and 22 of the fuse links, and in this way prevent a weakening of the links due to the tightening of the screws 13 and 14.

An important feature of my fuse is the means that I employ for ventilating the interior of the cylindrical member. This means consists of providing perforations 6, 7, 8 and 9 in each of the caps. In each of these perforations I place a thimble shown at 31. In Fig. 6 the outer edges of the thimble are turned over the adjacent portion of the cap, and the inner edges are turned outward, and then inward as shown at 32, and into the return bend formed at 32 I introduce a small disk of woven wire, mesh or gauze shown at 33. This mesh protects the perforations, provides ample ventilation for the interior of the fuse, and will usually prevent the rending of the fuse casting or the breaking of any of the parts thereof by the explosion or increased pressure due to the burning out of the fuse. As each of these ventilating perforations is protected by a gauze or mesh 33, gases under combustion or the flame or are due to the rending of the fuse cannot escape. The ignition or are will be quenched by the gauze 33 in a manner well understood.

The perforations 15 and 16 are arranged adjacent to the screw holes through which the screws 13 and 14 pass, therefore, a portion of the surface of the fuse link will be exposed through the perforations 15 and 16, and upon that portion of the fuse link I will stamp the capacity of the link. Thus in the Fig. 4 of the drawing the left hand fuse link is indicated at 150, showing that this link has a capacity of 150 amperes, the right hand link shows 200, indicating that this link has a capacity of 200 amperes.

It is obvious that I may use two fuse links of the same capacity and this will

probably be the general practice. I may weaken the fuse link in a manner other than by the perforations 26 and 27. It is also obvious that the depressions 28, 29 and 30 may be of any number and may be arranged in any desirable manner. Parts may be used without the whole, and other modifications made within the scope of the appended claims without departing from the principle or sacrificing the advantages of the invention.

Having carefully and fully described my invention what I claim and desire to secure by Letters Patents is—

1. A cartridge fuse having a cylindrical member, metallic cup shaped members secured one upon each end of said cylindrical member, movable contact members one adjacent to each of said cup shaped members and extending therethrough, each of said movable contact members having a plurality of lugs formed integral therewith, a fuse link, means for securing one end of said link between the lugs of one of said movable members and the cup shaped member adjacent thereto and means for securing the other end of said link between the lugs of the other of said movable members and the cup shaped member adjacent thereto.

2. A cartridge fuse comprising a cylindrical member of non-conductive material, metallic members secured one upon each end of said cylindrical member, a movable contact member adjacent to each of said metallic members and extending therethrough, lugs formed upon each of said movable contact members and arranged interior of said cylindrical member, and fuse links secured at their approximate mid-length between the lugs of one of said movable contact members and the metallic member adjacent thereto and having their free ends secured between the lugs of another of said movable contact members and the metallic member adjacent thereto.

3. A cartridge fuse having a cylindrical casing a fuse link within said casing, metallic cup shaped members arranged one upon each end of said casing each of said cup shaped members being provided with a plurality of perforations, thimbles secured in certain of said perforations, a woven wire member supported by each of said thimbles, and means passing through other of said perforations for retaining the said fuse link adjacent to certain other unoccupied perforations all combined for joint operation as herein set forth.

4. A cartridge fuse having a cylindrical member, and perforated metallic caps arranged one at each end thereof, thimbles secured in said metallic caps and supporting a gauze disk for ventilating the interior of said cartridge, as herein set forth.

5. A cartridge fuse comprising a cylindri-

cal member, metallic caps arranged one at each end thereof, contact members passing through said metallic caps, and each having a plurality of lugs, means for securing said 5 lugs to said caps and fuse links adapted to be secured between said lugs and said caps, and to extend through said cartridge as herein set forth.

Signed at New York city, county and State of New York, this 2nd day of April 1917.

HENRY MANNING COGAN.
